UNITED STATES PATENT OFFICE.

MARSTON E. STOKES, OF WORCESTER, MASSACHUSETTS.

FIREPLACE-DAMPER.

SPECIFICATION forming part of Letters Patent No. 732,380, dated June 30, 1903.

Application filed January 12, 1903. Serial No. 138,613. (No model.)

To all whom it may concern:

Be it known that I, MARSTON E. STOKES, a citizen of the United States, residing at Worcester, in the county of Worcester and 5 State of Massachusetts, have invented a new and useful Fireplace-Damper, of which the following is a specification.

This invention relates to a construction which has been designed for regulating the 10 draft of fireplaces.

The especial objects of this invention are to provide a simple and efficient form of throatway for connecting a fireplace with a chimney-flue in such a manner that an efficient 15 draft-passage will be provided of such shape and character that it will insure a proper fireplace-draft and will prevent back currents or downdrafts and also to secure the regulation of the draft by means of a simple 20 and efficient arrangement of damper-plates. To these ends this invention consists of the fireplace-damper and of the combinations of parts therewith, as hereinafter described, and more particularly pointed out in the claims 25 at the end of this specification.

In the accompanying drawings, Figure 1 is a sectional view of sufficient parts of a chimney and fireplace to illustrate the application of my invention thereto. Fig. 2 is an enlarged 30 perspective view of my improved construction, and Fig. 3 is a detail view of the operating-handle and its locking-disk.

One of the most annoying problems in building ordinary dwelling-houses is to provide 35 for the construction of open fireplaces so that an efficient draft will be maintained and down currents or back drafts avoided. This is due to the fact that slight changes in the shape of the throat or opening from the 40 fireplace into the chimney-flue oftentimes cause the fireplace to smoke or cause imperfect fireplace-drafts, and where the ordinary fireplaces are built by persons not experts in masonry construction or who have not made 45 a specialty of this work variations in the size of bricks or in the thickness of mortar seams will often lead to variations in dimensions of the fireplaces from those actually designed.

The especial object of this invention is to 50 provide a fireplace-fitting of simple and efficient form and which when built into place will provide a correctly-designed throatway

for connecting the fireplace and chimney-flue, while the draft of the fireplace may also be regulated by a simple and efficient arrangement of damper-plates. 55

Referring to the accompanying drawings for a detail description of a fireplace having my invention applied thereto, in Fig. 1 M designates the body portion or masonry in 60 which is formed the fireplace-opening A and the chimney-flue F.

A fitting constructed according to my invention for connecting the fireplace A and chimney-flue F, as most clearly illustrated in Fig. 2, comprises a metallic base-plate 10, which may be supported on three of its sides by the masonry M and may be supported at its front side by a cross-bar B. Extending up from the base-plate 10 and formed integrally therewith, if desired, is a hood 11, having a throat or passage opening up into the chimney-flue. In practice I have found that by the use of a throat-fitting for fireplaces of this shape I am enabled to secure an efficient 75 draft, while downdrafts will be avoided. The use of this fitting, furthermore, enables me to provide a simple and convenient arrangement of damper-plates. 70

As shown most clearly in Fig. 2, a number 80 of rods 13 are journaled transversely in the hood 11. At their rear ends the rods 13 are bent down or provided with crank-shaped sections, and connecting the crank-sections is a connecting rod or plate 14, which may be 85 held in place by nuts or cotter-pins, as shown. Mounted on each of the rods 13 is a damper-plate 12. One of the rods 13—for example, the central one—may be extended through to the front of the fireplace and provided with 90 a spring-pressed handle 15, which handle 15 has a tongue or lug which may be set into engagement with the desired notch in the disk 16 to hold the damper-plates 12 in their upright or open position, in inclined or partially- 95 closed positions, or in horizontal position when it is desired to completely close the passage between the fireplace and chimney-flue.

In a number of instances it has been proposed to provide swinging fireplace-dampers; 100 but in all such constructions with which I am familiar the damper-plates have swung laterally with respect to the fireplace-opening, and I have found in practice that the use of

such fireplace-dampers is objectionable, because they act as baffle-plates or deflectors, which are liable to deflect the smoke back into the fireplace when said dampers are partly closed, whereas by employing a plurality of damper-plates having a swinging motion widthwise with respect to the flue-opening reliability of draft will be obtained even when such dampers are inclined or partially closed.

10 I am aware that changes may be made in practicing my invention by those who are skilled in the art without departing from the scope thereof as expressed in the claims. I do not wish, therefore, to be limited to the 15 construction I have herein shown and described; but

What I claim, and desire to secure by Letters Patent of the United States, is—

1. As an article of manufacture, a fireplace-fitting, comprising a metallic hood adapted to be supported in the throatway between a fireplace and a chimney-flue, a plurality of transverse rods pivoted in the hood, a connection for causing the rods to turn in unison, a plurality of damper-plates carried by the rods, an operating-rod extending to the front of the fireplace, a handle for turning the rod, and a

locking mechanism on the outside of the fireplace for holding the dampers in different adjusted positions.

2. As an article of manufacture, a fireplace-fitting, comprising a metallic hood adapted to be supported in the throatway between the fireplace and a chimney-flue, a plurality of transverse rods pivoted in the hood, a connection 35 for causing the rods to turn in unison, comprising crank-sections on the ends of the rods outside of and at the rear of the hood in position not to be acted upon by the products of combustion, a link connecting the cranks, 40 damper-plates secured on the transverse rods, an operating-rod extending out to the front of the fireplace, a spring-pressed handle mounted on said rod, and a notched disk coöperating with said handle to hold the parts in different adjusted positions.

In testimony whereof I have hereunto set my hand in the presence of two subscribing witnesses.

MARSTON E. STOKES.
